UNITED STATES PATENT OFFICE.

ROBERT E. MCGAHEY, OF ALEXANDRIA, VIRGINIA.

ICE PICK.

Application filed September 14, 1921. Serial No. 500,571.

To all whom it may concern:

Be it known that I, ROBERT E. MCGAHEY, a citizen of the United States, residing at Alexandria, in the county of Alexandria and 5 State of Virginia, have invented certain new and useful Improvements in Ice Picks, of which the following is a specification.

My said invention relates to an improved ice pick and it is an object of the invention 10 to provide a device of this character which shall be combined with other tools so as to provide in combination with an ice pick in which the handle may be moved relatively to the head or not as desired, other 15 tools which normally are concealed within the handle.

Referring to the accompanying drawings which are made a part hereof and on which similar reference characters indicate similar 20 parts,

Figure 1 is a vertical elevation of my device partly in section, and

Figs. 2 and 3 are details.

In the drawings 10 indicates a handle having 25 a central cavity at 11. This handle is preferably flat at the upper end as shown and has a band 12 extending about said end to prevent excessive wear due to the use of the pick as a hammer in breaking up ice. At 30 the lower end is a cylindrical reduced portion encircled by a cap 13 having an inwardly extending flange 14 for holding the remaining parts of the pick in place with reference to the handle.

The pick proper comprises a shank 15 pointed at its lower end and having a head 16, a portion of the intermediate space being screw-threaded for the reception of a nut 17. In the use of the device the nut 40 17 is normally positioned at the lower end of the screw-threaded portion and limits the downward movement of the head relative to the pick member 15. The extent of the relative upward movement is determined by means of a nut 18 45 also on the threaded portion of the shank just below the head 16. Adjustment of these nuts relative to each other serves to determine the extent of movement of the handle 50 relative to the shank.

At the upper end of the member 15 a corkscrew 19 is inserted in the head 16 and preferably projects vertically upward therefrom. A hollow cylindrical member 20 55 surrounds the corkscrew when in the position

shown, said member having upwardly extending lips 21 and 22.

In the use of my device the nut 17 may be moved up against the flange 14, when the handle will have no movement relative to 60 the pick member. Adjustment of nuts 17 and 18 will if desired provide a variable amount of lost motion to vary the impact of the handle. The member 15 being removed from the handle by slipping the cap 13 off 65 the same, will leave the lips 21 and 22 exposed for use to remove metallic stoppers from bottles. If the member 20 is removed to expose the corkscrew this may then be inserted in a cork in ordinary manner to 70 draw the same. When the handle is thus separated from the remainder of the device it may be slipped over the point of the pick member to protect the hands of the user from injury, if desired. 75

Having thus fully described my said invention, what I claim as new and desire to secure by Letters Patent is:

1. An ice pick comprising a pick member having screw-threads adjacent its upper extremity, a pair of nuts thereon, a hollow handle surrounding said upper extremity of the pick member, and a cap embracing the lower portion of the handle and having a flange extending between said nuts, substantially as and for the purpose set forth. 80

2. In an ice pick, a pick member having screw-threads adjacent its upper extremity, a pair of nuts thereon, a hollow handle surrounding said upper extremity of 90 the pick member and adapted to be reciprocated on the pick member, the nuts limiting the length of the stroke, substantially as set forth.

3. In an ice pick, a pick member, a handle on one end thereof and slidable back and forth thereon for striking the pick member a hammer blow, and means for varying the stroke of the handle in both directions, substantially as set forth. 95

4. In an ice pick, a pick member having a pointed end, a handle slidably mounted on the other end of the pick member, a pair of nuts mounted on the pick member adapted to limit the movement of the handle in either 105 direction, and means for adjusting either or both of said nuts to vary the length of stroke of the handle, substantially as set forth.

5. An ice pick comprising a pick member, a hollow handle surrounding the upper part 110

of the pick member and adapted to enclose and conceal one or more tools, said handle having a reciprocating movement upon the pick member and having a pair of adjustable abutments to limit its motion in both directions, substantially as set forth.

In witness whereof, I have hereunto set

my hand and seal at Washington, District of Columbia, this 14th day of September, A. D. nineteen hundred and twenty-one. 10

ROBERT E. McGAHEY. [L. s.]

Witnesses:

E. W. BRADFORD,

O. M. KEYS.
